Patented July 8, 1919.

FIG. 1

FIG. 4

FIG. 2

INVENTOR
GEORGE A. REYNOLDS

BY
Lockwood Lockwood,
ATTORNEYS.

UNITED STATES PATENT OFFICE.

GEORGE A. REYNOLDS, OF INDIANAPOLIS, INDIANA.

VALVE-OPERATING MECHANISM.

1,309,339.

Specification of Letters Patent.

Patented July 8, 1919.

Application filed June 20, 1918. Serial No. 240,894.

To all whom it may concern:

Be it known that I, GEORGE A. REYNOLDS, a citizen of the United States, and a resident of Indianapolis, county of Marion, and State 5 of Indiana, have invented a certain new and useful Valve-Operating Mechanism; and I do hereby declare that the following is a full, clear, and exact description thereof, reference being had to the accompanying drawings, in which like numerals refer to like parts.

This invention relates to a valve operating means for engines and the prime object of the invention is the provision of means for 15 mechanically opening and closing the valve.

A further feature of the invention is the provision of yielding means in connection with the stem of the valve and the operating lever therefor and means to compensate for 20 any variation in the parts of the valve through expansion or contraction.

A further feature of the invention is the provision of means to prevent the parts of the device from rattling or making unnecessary noise by the parts of the device working together, and a further feature of the invention is the provision of a cam structure which will positively operate the valve and hold the valve operating parts in proper 30 alinement and against any twisting movement.

Other objects and advantages will be hereinafter more fully set forth and claimed.

In the drawings, Figure 1 is a vertical 35 sectional view through a part of an engine cylinder, showing the valve operating mechanism with the valve in closed position. Fig. 2 is a similar view thereof showing the valve in open position. Fig. 3 is an edge elevation 40 partly in section of the valve operating cam wheel and parts coöperating therewith, and Fig. 4 is a detail sectional view as seen on line 4-4 of Fig. 2.

Referring to the drawings in which similar reference numerals designate corresponding parts throughout the several views, 1 indicates the cylinder of an engine which may be of the usual or any preferred construction, and 2 indicates the head of the cylinder, said 50 head having a port 3 therein, and a valve seat 4 in the lower wall thereof, through which propelling material may pass from the port to the cylinder of the engine.

Coöperating with the seat 4 is a valve 5, said valve having a stem 6, which passes upwardly through a bearing 7 in the head and

projects a distance above the head. Coöperating with said stem 6 above the bearing 7 is a rocking lever 8 which is pivoted at its longitudinal center between ears 9 projecting upwardly from the head 2. Both ends of the rocking lever 8 are bifurcated as shown in Fig. 4, the arms 10 at the inner end of the lever passing on opposite sides of the stem 6, the upper and lower edges of said arms being oval shaped so that they will have rocking action with the parts with which they engage.

The projecting end of the stem 6 is provided with threads 11, nuts 12 being turned on to the threads 11 and so positioned upon the stem 6 that the lower face of the arms 10 will rest thereon. The arms 10 are held against the nuts 12 through the medium of the coil spring 13, the lower end of which rests upon the washer 14 surrounding the stem 6, while the upper end thereof bears against a plate 15 also surrounding the stem 6, the plate being held in adjusted position on the stem by means of a nut 16. The tension of the spring is such as to normally cause practically unyielding action of the valve, but is so arranged that any contraction or expansion of the valve or its stem will be accommodated, thus holding the adjustment between the valve stem and the lever uniform at all times.

The lever 8 is rocked upon its pivot through the medium of a cam wheel 17 and a pitman 18, the cam wheel 17 being keyed to a driven shaft 19, so as to positively rotate the cam wheel. The upper end of the pitman 18 is threaded and the end of the rocking lever 8 coöperating therewith is likewise bifurcated to provide arms 20 which pass on opposite sides of said pitman, the upper and lower edges of said arms being rounded or formed oval so that they will have rocking action with the parts with which they contact.

The lower edges of the arms 20 bear against the washer 21, while the upper edges of said arms bear against nuts 22 threaded on to the upper end of the pitman 18. In order to prevent pounding noise or rattling between the arms 20 and the washer 21 and nuts 22, a cup 23 is threaded on to the pitman 18 before the washer and nuts are placed thereon and in said cup is placed a tension spring 24 which bears against the lower face of the washer 21 and holds the same in close proximity to the lower faces

of the arms 20 and holds the upper edges of said arms against the lower face of the nuts.

Attached to the lower end of the pitman 5 18 is a slide block 25 which is preferably square in cross section and extends through a bearing 26 which has an opening therethrough to receive the slide block. Attached to the lower end of the slide block 25 and 10 on opposite sides thereof are rollers 27 which rollers engage cam channels 28, so that when the cam wheel is rotated the pitman 18 will be moved longitudinally to open or close the valve 5. The cam wheel is preferably formed of twin parts which are faced against each other, the registering channels 28 for receiving the rollers 27 being on the inner meeting faces of the sections of the cam wheel so as to exclude the same from 15 view, and also for holding the pitman and the slide block against rotation and in proper alignment.

The slide block 25 enters a peripheral groove 29 formed around the cam wheel and 20 between the meeting faces of the two sections thereof.

By this construction it will be seen that the valve will be positively moved in both directions mechanically and by properly arranging the cam wheel the operation of the valve will be properly timed for opening and closing.

It will likewise be seen that by providing yielding means for holding the ends of the 30 rocking lever in engagement with their co-operating parts, that any noise or rattling or wear will be eliminated and compensated for. It will further be seen that as there

are practically no parts to become worn the device will last indefinitely and can successfully be applied to any preferred make of engine requiring valves for controlling the admission of propelling medium thereto.

The invention claimed is:—

1. In a valve operating mechanism, the 45 combination with a valve having a stem, of a pivotally mounted operating lever, means for connecting one end of the lever to the valve stem, yielding means for holding the end of the lever against parts of the valve 50 stem, a pitman co-operating with the opposite end of said lever, means on the pitman above the lever against which the end of the lever bears, a spring below the end of the lever for holding the end of the lever 55 against the bearing parts of the pitman, a cup threaded onto said pitman for carrying said spring, and a cam wheel for operating said pitman, whereby the valve will be positively opened or closed.

2. In a valve operating mechanism, the combination with a valve having a stem, of a pivotally mounted lever, having bifurcated ends, a spring structure carried by the valve stem, for directing pressure against one end 65 of the lever, a pitman co-operating with the opposite end of the lever, a spring carried by the pitman for directing pressure against the end of the lever co-operating with the pitman, rollers carried by the pitman, and a cam wheel having cam channels therein in which the rollers travel.

In witness whereof, I have hereunto affixed my signature.

GEORGE A. REYNOLDS.
